UNITED STATES PATENT OFFICE.

PER JOHAN HEDLUND, OF STOCKHOLM, SWEDEN.

STEAM-TURBINE.

SPECIFICATION forming part of Letters Patent No. 761,226, dated May 31, 1904.

Application filed March 30, 1903. Serial No. 150,253. (No model.)

To all whom it may concern:

Be it known that I, PER JOHAN HEDLUND, of Stockholm, Sweden, have invented a new and useful Improvement in Steam-Turbines, of 5 which the following is a specification.

The invention relates to an elastic-fluid turbine, and more particularly to a series of said turbines compounded and secured upon the same shaft.

10 The invention consists, first, in the supporting of the entire turbine upon projections extending from its ends or heads, so that the casing may yield downward under the weight of the parts coincidently with the shaft, and thus 15 unequal wear of the joints between casing and shaft and possible leakage at such joints is prevented.

The invention further consists in the construction of the wheel and also in the mode of 20 attaching thereto the buckets, as hereinafter more particularly pointed out.

In the accompanying drawings, Figure 1 is 25 a side elevation of a compound steam-turbine with the casing-wall broken away to show the internal construction. Fig. 2 is an enlarged partial section on the line *x x* of Fig. 3, showing the construction of the wheel-hub and of the buckets. Fig. 3 is an enlarged detail cross-section on the line *y y* of Fig. 2.

30 Similar numbers of reference indicate like parts.

The general construction of the compound steam-turbine embodying my present improvements is the same as is set forth in Letters Patent No. 717,875, granted to Tore G. E. Lindmark January 6, 1903.

1 is the casing, here shown as constructed in a number of sections united by the bolts 2. Through said casing extends the wheel-shaft 40 3, the said shaft passing loosely through the cylindrical projections 4 on the casing-heads 5 6. The heads are each divided horizontally, into two sections, so that one half of each projection 4 is on the upper half-section and the 45 other half on the lower half-section of each head. The projections 4 are received in cylindrical bearings 7 on the inner sides of the standards 8, in which standards the shaft 3 is journaled. The upper halves of the bearings 50 are removable. The lower half projection on

head 6 has a flange 9, which enters a corresponding channel in the lower half of the cylindrical bearing 7. Hence when the upper half or cover 10 of the bearing is secured in place the edges of said cover meet the shoulders on the ends of half-flange 9, and in this way the casing is prevented from rotation in its supports. 55

It is to be especially noted that the casing 1 is not supported anywhere except by the 60 projections 4 at the ends and is raised clear of the floor or ground beneath it. I find that when the casing is supported from a bed-plate integral with the standards 8 or rests directly on the ground then the shaft under the weight 65 of the wheels is apt to sag downwardly in the casing, which is prevented from similar yielding. The result is that it becomes difficult to keep the joints around the shaft steam-tight and to avoid unequal wear. On the other 70 hand, when the casing is supported at its ends in the same way as the shaft both casing and shaft yield equally and the difficulty is overcome.

Internally the casing 1 is divided into chambers A B C, &c., in each of which is a chamber *a b c*, &c., for the reception of the wheels I II III. The wheel-chambers *a b*, &c., each communicates with its surrounding chamber A B, &c., by means of the flaring passage *d*, 75 80 the purpose and effect of which is fully set forth in the aforesaid Lindmark patent.

The working fluid is first led into the wheel I through the central aperture thereof and then passes circumferentially from said wheel 85 to the passage *d*, and so to the chamber A. After traversing wheel II and associated passage *d* it goes to chamber B, and so on through all of the wheels successively to the exhaust, which may be at D. The wheels, chambers, 90 and passages are made of gradually-increasing area to allow of expansion of the steam, and the combined effect of all of the wheels is of course exerted upon the shaft 3.

The shaft 3 is of stepped form and tapers 95 preferably from the center to the ends. The wheel-hubs 11 are internally tapered to fit upon the parts of the shaft of corresponding diameter and are driven upon said parts, so that they become tightly held thereon. 100

In Fig. 1 I show but one wheel on each tapered section; but it will be understood that I may apply to each section several wheels by making said sections of suitable length. 5 The construction of the shaft in tapered sections and of the wheel-hubs to fit on said sections provides a very strong and firm mode of securing said wheel-hubs on the shaft.

The construction of the wheel, which is 10 illustrated in Figs. 2 and 3, is as follows: One head 13 of the wheel is formed integral with the hub 11 and is provided with a flange 14 to receive the wall 15 of its receiving-chamber *a*. The other head of wheel 16 is flanged at 17, 15 and between the flange and the hub is inserted a double-rimmed spider 18, one rim, 19, of which bears upon the hub 11, and the other rim, 20, comes beneath the flange 17. In this way the head 16 is supported from the hub, 20 while inlet of steam to the wheel is permitted through the openings 21 between the spider-arms 22. The head 16 may also be connected to the head 13 by riveted studs 23. The circumferential edges of the heads 13 and 16 are 25 bent inwardly, so as to produce the contracted steam-escape opening 24. All around the wheel and in this opening are placed the buckets 25, which are secured therein in the following manner: On the inner faces of 30 heads 16 and 13 are milled straight recesses 26, which are adapted to receive the longitudinal edges of the buckets 25. The recesses 26 are suitably inclined in order to give the buckets the desired inclination. At the inner 35 ends of the buckets are formed eyes, through which pass the rivets 27, these rivets being set up at their ends in the heads 16 13. In placing a bucket in the wheel it is first inserted at its edge into a recess in head 13, and 40 then the opposite head 16 is applied so as to bring the outer or free edge of the bucket into the recess of that head, and then the rivet is thrust through the openings in the two heads and also through the eye in the end of the 45 bucket, which comes between said openings, after which the rivet is secured as already stated.

I claim—

1. A turbine-wheel, a stationary casing 50 therefor, centrally-disposed projections on opposite sides of said casing, a shaft carrying said wheel and extending through said projections, fixed standards receiving said projections, and half-flanges on said projections received in said standards.

2. In a compound elastic-fluid turbine, a cylindrical casing, centrally-disposed projections on the ends thereof, fixed standards receiving said projections, a shaft extending 60 through said projections and journaled in said standards and a plurality of wheels on said shaft.

3. In a compound elastic-fluid turbine, in

combination with a cylindrical casing centrally-disposed projections on the ends thereof, a shaft extending through said projections, and a plurality of wheels on said shaft, two fixed standards provided with cylindrical recesses to receive said projections and journal-bearings for said shaft. 65

4. In a compound elastic-fluid turbine, a shaft having a plurality of tapering steps and wheels having hubs internally formed to fit tightly on said steps. 70

5. In a compound elastic-fluid turbine, a shaft having a plurality of tapering steps of progressively-increasing diameters and wheels having hubs internally formed to fit tightly on said steps. 75

6. In a compound elastic-fluid turbine, a shaft having a plurality of tapering steps of progressively-increasing diameters from the ends of the shaft to the middle thereof and wheels having hubs internally formed to fit tightly on said steps. 80

7. In an outward-flow elastic-fluid turbine, a hub, a wheel-head supported thereon, a spider on said hub, an annular wheel-head inclosing said spider and means for connecting said wheel-heads. 85

8. In an outward-flow elastic-fluid turbine, a hub, a wheel-head integral therewith, a spider on said hub, an annular wheel-head having an internal flange, the said flange inclosing the said spider and means for connecting said wheel-heads. 90

9. In an elastic-fluid turbine, two wheel-heads each having a recess at its circumference and on its inner side, a bucket disposed between said heads and having its edges in said recess and provided at its inner end with an eye, and a securing-bolt for said bucket passing through said wheel-heads and said bucket-eye. 95

10. In an elastic-fluid turbine, two wheel-heads having their circumferential edges inwardly inclined to form a contracted annular escape-opening and provided with recesses having straight radial walls formed on the inner sides of said contracted portions, a bucket disposed between said heads and having its edges in said recesses and provided at its inner end with an eye, and a securing-bolt for said bucket passing through said wheel-heads and said eye. 105

11. In combination with a turbine-wheel, a non-rotating cylindrical casing and supports therefor located only at the ends thereof; the said supports and said casing being coaxial. 110

In testimony whereof I have signed my name to this specification in the presence of two subscribing witnesses. 115
